UNITED STATES PATENT OFFICE.

JOHN HOPE AND JOHN HOPE, JR., OF PROVIDENCE, RHODE ISLAND.

DESIGN FOR A FRAME FOR PANTOGRAPH ENGRAVING-MACHINES.

SPECIFICATION forming part of Design No. 28,996, dated July 5, 1898.

Application filed June 13, 1898. Serial No. 683,364. Term of patent 14 years.

To all whom it may concern:

Be it known that we, JOHN HOPE and JOHN HOPE, Jr., of Providence, in the county of Providence and State of Rhode Island, have 5 invented and produced a new and original Design for a Frame for Pantograph Engraving-Machines, of which the following is a specification, reference being had to the accompanying drawings, forming part thereof.

10 Figure 1 is a front elevation of the frame for supporting the mechanism of a pantograph engraving-machine, showing our design. Fig. 2 is an end view, and Fig. 3 a transverse sectional view, of the same.

15 The leading features of our design consist in the inclined surfaces of an extended base, having an arched opening in the front of the lower part of the frame, and the arched table supported at the opposite ends of the upper 20 part of the frame.

In the drawings, *a a* indicate the inclined surfaces of the sides of the lower standard or frame connected by the curved surfaces *b b* with the extended base *c c*. In the front is 25 the arched opening *d*, having the marginal bead *e*. The lower part is surmounted by the projecting table *f*. The upper part of the frame has the end supports resting on the ends of the table *f*, as shown in Fig. 2. These

end supports *g g* curve inward at their lower 30 ends and then extend upward, spreading outward when viewed endwise, while viewed from the front the end supports extend upward perpendicularly until they meet the curves *i i*, where they extend outward to support the projecting ends of the table *K*. At the inner sides the end supports merge into the curves *h h*, which extend inward to the lower line of the table *K*. The table *f* forms the support of the pattern-table, the stylus-carriage, and the stylus-frame, while the table *K* forms the support of the roll to be engraved and the actuating mechanism controlling the gravers. 35 40 45

Having thus described our invention, what we claim as new, and desire to secure by Letters Patent, is—

The design for a frame for pantograph engraving-machines herein shown and described. 50

In witness whereof we have hereunto set our hands.

JOHN HOPE.
JOHN HOPE, JR.
